CLAIM

The ornamental design for a toe protector for athletic footwear having removable cleats, as shown and described.

DESCRIPTION

FIG. 1 is a perspective view of a toe protector for athletic footwear having removable cleats, showing my new design; FIG. 2 is a bottom view thereof;

FIG. 3 is a top view thereof;

FIG. 4 is a right side view thereof;

FIG. 5 is a left side view thereof;

FIG. 6 is a front view thereof; and,

FIG. 7 is a rear view thereof.

The broken lines in the drawings in FIGS. 1-7 are for illustrative purposes only and form no part of the claimed design.

1 Claim, 7 Drawing Sheets
